UNITED STATES PATENT OFFICE.

HENRY B. ROBISCHUNG, OF KALAMAZOO, MICHIGAN, ASSIGNOR TO THE NATIONAL HOLLOW BRAKE BEAM COMPANY, OF CHICAGO, ILLINOIS.

TRUSS ED BRAKE-BEAM.

SPECIFICATION forming part of Letters Patent No. 440,438, dated November 11, 1890.

Application filed September 5, 1890. Serial No. 364,036. (No model.)

To all whom it may concern:

Be it known that I, HENRY B. ROBISCHUNG, a citizen of the United States, residing at Kalamazoo, in the county of Kalamazoo, State of Michigan, have invented certain new and useful Improvements in Trussed Brake-Beams; and I hereby declare the following to be a full, clear, and exact description thereof, reference being had to the accompanying drawings, 10 wherein—

Figure 1 is an elevation, partly in section, of a portion of a six-wheel truck, one wheel thereof, and sufficient of the brake-beam and levers to illustrate my invention. Fig. 2 is a 15 detached enlarged view of strut or post for trussed brake-beams embodying my invention, with portions of the beam and truss-rod sufficient to illustrate the connections and relations of the strut or post. Fig. 3 is a 20 detached side elevation of the strut or post, or a view at right angles to Fig. 2. Fig. 4 is a detached view of the nose-piece or draft-block of the strut or post.

Like symbols refer to like parts wherever 25 they occur.

My invention relates to the construction of trussed brake-beams for six-wheeled trucks, such as are commonly used under passenger and sleeping cars, and has for its object to 30 strengthen the truss or post and relieve the truss-rod of strain by transferring the pull or strain to the strut or post back of the truss-rod and to the beam, and also to take up any slack in the beam, or, in other words, to apply 35 the power to the trussed structure with like effect as is now done by levers acting on the strut or post between the truss-rod and beam, so as to bring out the full strength of the structure.

40 In the case of trussed brake-beams for ordinary four-wheel trucks the arrangement and space are such that the brake-levers can be pivoted on the strut or post between the truss-rod and beam and the pull-rods connected to the 45 brake-levers; but with six-wheel trucks it becomes necessary to connect the pull-rod directly with the nose or outer end of the strut. (Indicated in Fig. 1 of the drawings.) As a result of such connection the draft-strain is 50 brought on the weakest and least supported

portion of the structure and is transferred from the strut to the truss-rod or tension-rod, which precludes the taking up of any lost motion or slack in the beam, and as a result the full strength of the trussed structure is not 55 brought out and the fracture of the nose of the strut or that portion to which the pull-rod is attached is liable to occur. In order to overcome said objections I combine with the strut or post a projecting nose-piece or nose-block for the attachment of the pull-rod, said nose-piece so bolted or otherwise secured to the strut or post as to transfer the strain or pull to the strut or post back of the tension-rod and thence to the beam, while allowing 60 the tension-rod or truss-rod the same freedom of adjustment it possesses in trussed beams as now constructed.

I will now proceed to describe my invention more fully, so that others skilled in the art to 70 which it appertains may apply the same.

In the drawings, A indicates a brake-beam, which in a trussed structure occupies the position of the rod; B, the tension-rod or truss-rod; C, the strut or post, and D the brake-head. In Fig. 1 of the drawings said structure 75 is for purposes of illustration shown in position or as applied to the wheel E of a six-wheel truck, being suspended by the two hangers a b and operated by the series of pull-rods c d e f and intermediate levers g h, the latter suspended by the hanger i, though, as the system of pull-rods and levers form no part of the present invention, any other arrangement thereof may be used.

80 The strut or post C, which embodies the main points of the invention, I usually form as a solid or ribbed post throughout the portion l, omitting the usual lever-slot, but retaining on the outer end of the post proper 85 the usual concave seat 2 for the reception of the truss or tension rod, and I bifurcate or slot the post proper at its outer end transversely of the tension-rod C, as at 3, for the reception of a nose-piece or nose-block 4. 90 On the outer end of the post proper I also provide perforated lugs or eyes 5 for the second hanger b, and such lugs also strengthen the post at that point. Just back of the end 95 of the post, but through the slotted portion 100

thereof, is a bolt-hole for the bolt 6, which secures the nose-block to the post.

The nose-block 4 is provided with a bolt-hole 7 for the passage of bolt 6, said bolt-hole 5 of such size as to prevent any play of the nose-block in the slot of the post and so placed as to insure the end of the block 4 fitting squarely on the bottom of the slot in the end of the post. At a point corresponding with the seat 10 3 for the tension or truss rod a second hole 8 is formed for the passage of the truss-rod B, and said hole 8 is sufficiently larger than the cross-sectional area of the truss-rod to leave the truss-rod free and prevent any strain or 15 tension thereon from the pull on the nose-block. Near the outer end of the nose-block is a third hole 9 for the attachment of the pull-rod c or its equivalent.

In practice I prefer to form the post proper 20 20 of malleableized cast-iron, as is now commonly done in such structures, and to form the nose-block of steel or equivalent material capable of resisting great tensile strain, but do not herein limit myself to any particular 25 metals, as any of suitable character may be used at will.

Having thus described my invention, what I claim, and desire to secure by Letters Patent, is—

1. The combination, with the post of a 30 trussed brake-beam, of a pull or nose block, substantially as and for the purposes specified.

2. A strut or post for trussed brake-beams, 35 said post slotted at its outer end and provided with a pull or nose block, substantially as and for the purposes specified.

3. The combination, in a trussed brake-beam, of a tension or truss rod and a strut or post having a nose or pull block provided 40 with a hole for the passage of the tension-rod, said hole being larger than the cross-sectional area of the tension-rod, substantially as and for the purposes specified.

In testimony whereof I affix my signature, in 45 presence of two witnesses, this 30th day of August, 1890.

HENRY B. ROBISCHUNG.
